ATTYS.

UNITED STATES PATENT OFFICE.

CHARLES ERRETT, OF NEW YORK, N. Y., ASSIGNOR TO PUBLIC SERVICE CUP COMPANY,
OF BROOKLYN, NEW YORK, A CORPORATION OF NEW YORK.

PAPER-CUP HOLDER.

1,280,692.

Specification of Letters Patent.

Patented Oct. 8, 1918.

Application filed November 7, 1916. Serial No. 130,054.

To all whom it may concern:

Be it known that I, CHARLES ERRETT, a subject of the King of Great Britain, and resident of the city of New York, in the 5 State of New York, United States of America, have invented certain new and useful Improvements in Paper-Cup Holders, of which the following is the specification.

10 This invention relates to improvements in paper cup holders, and the objects of the invention are to provide a simple and effective form of container for paper cups which will permit the number of cups in the container to be readily observed and permit only one cup to be withdrawn at a time.

Further objects are to provide such a holder or container which may be conveniently used on a desk or table, and the invention comprises the improved construction hereinafter described in detail in the accompanying specification and drawings.

In the drawings,

Figure 1 is a sectional perspective view of 25 an embodiment of the invention.

Fig. 2 is a cross section showing the means for preventing the withdrawal of more than one cup at a time.

Fig. 3 is a sectional perspective view indicating an alternative form of retaining means for the cup.

Fig. 4 is a sectional perspective view indicating still another alternative form of retaining means.

Fig. 5 is a sectional view of another alternative form of retaining means.

Fig. 6 is a sectional view indicating another form of retaining means.

In the drawings like characters of reference indicate corresponding parts in the several figures.

Referring to the drawings, A represents a container which may be made of any suitable material, such as sheet metal or celluloid, card board, etc. The container is conveniently cylindrical in form and provided with a weighted base 10. The sides of the container are such as to receive a stack or nest of paper cups B, which are inverted 50 before placing in the container, whereby their rims will project outwardly at the bottom of the stack as shown.

C represents the cover or top portion closely surrounding and adapted to telescope

upon the container A. The top cover is also 55 cylindrical in form and is either wholly transparent or formed with a transparent cap 11 as shown, which may for instance, be formed of transparent celluloid. This transparent portion and the cap permits the number of cups within the container to be readily observed. Celluloid when used in the cover has the advantage of being light and flexible. It is also repellent to moisture so that the 60 moisture from the room in which the container is placed will not condense on the cover to contaminate the same.

It will also be noted that the cover and container may be telescoped together to correspond with the height of the stack. To 65 relieve the pneumatic pressure produced when the cover and container are telescoped together, an air hole 12 may be provided in the cap 11 or at any other convenient point.

Means are provided at the top of the container whereby the stack will be freed or released from the uppermost and outermost cup when the same is withdrawn by a person desirous to use the same. A considerable variety of means may be used for this purpose. 70 In Figs. 1 and 2 I have shown a plurality of circumferential slots 13, provided around the periphery of the container near the top thereof, in which slots an elastic band 14, is adapted to lie. To prevent this band from projecting outwardly from the periphery of the container, an annular groove 15 may be provided in the periphery of the container to receive the band.

In using the container, the person desirous of obtaining a cup, first removes the cover portion C, then grasps the uppermost and outermost cup on the stack and raises the same. The rim on the cup will engage the elastic band 14, and will cause the operator to move the cup slightly laterally or oscillate the same in order to disengage the same from the band, whereupon the band will engage the rim of the next cup and so retain it and prevent the stack being withdrawn with the cup. The elastic will also serve in assisting to return the stack to its 90 normal position.

In Fig. 3, tongues 17 and 18 are provided on opposite sides of the container, slightly 105 staggered with respect to each other, whereby the cup must be tilted slightly before withdrawal.

In Fig. 4 a semi-annular spiral wire 19 is provided on the inner wall of the container. This wire or rib will necessitate slightly tilting of the outermost cup before 5 removing.

In the form shown in Fig. 5 the staggering ratchet teeth 20 and 21 are provided on opposite sides.

In Fig. 6 a plurality of inwardly bent 10 spring tongues 22 are provided for the same purpose.

As many changes could be made in the above construction and many apparently widely different embodiments of my invention 15 within the scope of the claims constructed, it is intended that all matter contained in the accompanying specification and drawings shall be interpreted as illustrative and not in a limited sense.

What I claim as my invention is:

1. A holder for paper cups and the like, comprising a container formed with circumferential slots, an elastic extending in said slots adapted to engage the rims of the cups placed in the container. 20

2. A holder for paper cups and the like, comprising a container having an annular groove in the wall thereof and circumferential slots in the groove and an elastic extending in the slots adapted to engage the rims 25 of the cups placed in the container.

In witness whereof I have hereunto set my hand in the presence of two witnesses.

CHARLES ERRETT.
